UNITED STATES PATENT OFFICE

96,793

DESIGN FOR A CAN OPENER

Ozro N. Wiswell, Los Angeles, Calif.

Application June 22, 1934, Serial No. 52,279

Term of patent 14 years

To all whom it may concern:

Be it known that I, Ozro N. Wiswell, a citizen of the United States, residing at Los Angeles, in the county of Los Angeles, State of California, have invented a new, original, and ornamental Design for a Can Opener, of which the following is a specification, reference being had to the accompanying drawings, forming part thereof.

Fig. 1 is a side elevational view of the can opener, showing my new design;

Fig. 2 is an elevational view of the inner side thereof;

Fig. 3 is an elevational view of the outer side thereof; and

Fig. 4 is a perspective view of the inner side thereof.

I claim:

The ornamental design for a can opener, as shown.

OZRO N. WISWELL.
